SOLDERLESS CONNECTER

Charles L. Peirce, Jr., Pittsburgh, Pa., assignor of
one-half to Hubbard and Company, a corpora-
tion of Pennsylvania

Application April 4, 1933, Serial No. 664,341

7 Claims. (Cl. 173—263)

This invention relates to solderless connectors such as are adapted to join or connect electrical conductors. Such connectors are used quite extensively for connecting or attaching service conductors to main feeder lines, for connecting transformer leads to power supply conductors, and for other analogous purposes.

The majority of solderless connectors used in the past and those now supplied to the trade were 10 constructed substantially in accordance with the disclosure of United States Patent No. 1,206,044 dated November 28, 1916.

One of the chief objections to such prior art connectors was that in order to attach the same 15 to main or feeder conductors, for example, it was necessary to take the connectors apart. Since the main conductors were almost always charged or live, it was customary for the workmen when attaching the connectors, to work with rubber 20 gloves, and for this reason the parts thereof were frequently dropped. Instead of replacing the part which was dropped, many workmen threw the connector away and started with a new one. This practice, therefore, resulted in waste of connectors and also loss of time.

An object of this invention is the provision of a connector in which the component parts thereof will always be maintained in assembled relation to each other when it is prepared for attachment to conductors.

Other objects of the invention will, in part, be apparent and will, in part, be obvious from the following description taken in conjunction with the accompanying drawing, in which:

35 Figure 1 is a view in side elevation showing a connector constructed in accordance with an embodiment of the invention, and in operative relation to a pair of conductors which have been connected thereby;

40 Fig. 2 is a view taken at right angles to the view in Fig. 1 showing the relative position of the component parts of the connector to the conductors, one part of the connector being shown in a broken line position to indicate the relative position of that part of the connector when it is in condition to be removed from the conductors or in preparation for attachment thereto;

45 Fig. 3 is a top plan view of an element embodied in the makeup of the connector;

50 Fig. 4 is a view in side elevation of the connector part shown in Fig. 3;

Fig. 5 is a view in side elevation of a contact block embodied in the connector;

55 Figs. 6 and 7 are end elevation and top plan

views respectively, of the contact block shown in Fig. 5;

Fig. 8 is a view in side elevation of a connector embodying a modified form of the invention;

Fig. 9 is a side elevational view of a contact block associated with a part of the connector in Fig. 8;

Fig. 10 is a view in side elevation showing a still further modified form of connector in its operative relation to a pair of conductors which have been connected thereby;

Fig. 11 is a view of the connector shown in Fig. 10 taken at right angles thereto, a part of the connector being shown in a broken line position when the connector may either be removed from the conductors or applied thereto;

Fig. 12 is a view of one part of the connector of Figs. 10 and 11, a part thereof being shown in section taken on line XII—XII of Fig. 13; and

Fig. 13 is a top plan view of the connector part shown in Fig. 12.

Throughout the drawing and specification like reference characters indicate like parts.

In Figs. 1 to 7 of the drawing, a connector 1, embodying one form of invention and its component parts, are shown. This connector is adapted to join conductors, particularly electrical conductors. Connectors of this type are used largely for connecting a service conductor to a feeder conductor, although they may be and frequently are utilized for connecting transformer leads to power supply conductors, and for other analogous purposes. In the drawing, the connector is shown as joining a service conductor 2 to a main or feeder conductor 3.

Connector 1 comprises clamp parts 4 and 5 which hold the conductors together in line contact with each other at their point of tangency. In order that the clamp parts may be maintained intact or in assembled relation when prepared either for removal from or attachment to the conductors to be joined, means 6 are provided. Means 6 permits a predetermined amount of movement between the respective clamp parts when preparing them for attachment to or removal from the conductors but will not permit accidental disassociation or complete separation thereof. Therefore, the linemen may handle these connectors freely without danger of dropping or losing any of the clamp parts.

Clamp part 4 comprises a bolt having a polyhedral head 8 and a threaded bifurcated shank 9. Shank 9 may be considered as a yoke of U-shape having spaced legs 10 and 11 joined at 55

adjacent ends by the head 8. The head may be grooved or recessed as at 12 to provide a seat for one of the conductors.

Clamp part 5 comprises a nut 13 and a contact block or member 14 (see Figs. 5, 6 and 7), the nut being adapted to be threaded on or off shank 9 and the contact block being turnably mounted in the opening of the nut, so that these two parts may move together.

10 Contact block 14 may be formed in a die from a sheet or blank of copper and so shaped as to provide a body portion 15, substantially rectangular in transverse section, adapted to extend through the nut, and having a side wall 16, end walls 17 and a top wall 18, the bottom and side opposite wall 16 being open.

15 The top wall 18 is of greater length than the diameter of the opening in the nut so that the nut forms a backing therefor when the clamp parts are drawn together about the conductors. The top face of wall 18 may be grooved or recessed as at 19 to form a seat for one of the conductors to be joined or connected to another conductor.

20 25 The depth of block 14 is such that there will be sufficient space on either side thereof to accommodate the legs of the bifurcated bolt shank when the contact block is between them as shown in Fig. 2.

30 35 In order that the contact block may be locked in the nut, the lower ends of side walls 17 may be bent outwardly as at 20 (see Figs. 1 and 5), so as to overlap the bottom face of the nut.

Means 6 which is provided to maintain nut 13 and contact block 14 in assembled relation to clamp part 4 may comprise a strip 21 of metal adapted to lie along the inside face of one or the other of legs 9 and 10, for example, leg 9, and to extend through the nut to one side of contact block 14.

40 45 The upper end of the strip is bent laterally and provided with an opening 22 adapted to fit the contour of leg 9 and frictionally engage the same so that the strip will be held in the position shown in Fig. 2. The lower end of the strip terminates in a hook 23 adapted to catch or engage the lower edge of side 16 of the block when the nut is removed from the bolt shank as indicated in Fig. 2 by the broken line position of the nut and block. The lower portion of the strip including the hook may be strengthened and rigidified by forming a corrugation therein such as indicated at 24.

50 55 To join a pair of conductors by means of the connector above described, particularly when one of the conductors is a through conductor, the nut is removed from the bolt shank and permitted to rest on the hook 23 (see Fig. 2). The conductor 3 is then slipped through the space between nut 13 and the end of leg 11 and the connector shifted so that the legs 9 and 10 straddle the conductor. The nut may now be threaded on the shank.

55 60 65 The dead-end or service conductor 2 is next passed through the bolt shank between the head 8 and through-conductor 3 and centered on the same, as shown in Fig. 2. While the conductors are held centered as above described, the nut is drawn up tightly until the conductors are 70 firmly and securely clamped together. Having joined the conductors in this manner, the connector may be wrapped with tape as is customary practice.

75 In Fig. 8 of the drawing a connector 26, embodying a modified form of the invention, is

shown which comprises a clamp part 27 and a clamp part 28, means 29 being provided to hold the clamp parts in assembled relation when prepared either for attachment to or removal from conductors such as conductors 2 and 3 illustrated in Figs. 1 and 2.

Clamp part 27 may comprise a bolt having a polyhedral head 30 and a threaded bifurcated shank 31, similar to the shank of the connector illustrated in Figs. 1 and 2, between which the 10 conductors may be placed.

Clamp part 28 comprises a contact block 32 which extends through a nut 33 and is turnably supported thereby. The contact block comprises a body portion 34 of substantially inverted U-shape having a transverse portion 35, the ends of which lie across nut 33. The upper face of the transverse portion is recessed or grooved as at 36 to form a seat for one of the conductors to be clamped or joined by the connector. The 20 ends of the legs of the U-shaped body portion may be bent outwardly as at 37 to engage the bottom face of the nut and thereby lock the contact block thereto. The thickness of the contact block is such that it may extend through the 25 space between the legs of the bifurcated shank and provide sufficient clearance on either side thereof through which the legs of the bifurcated member may pass as the nut is threaded on or off the same.

30 35 The means 29 which is provided to hold the nut and contact block in assembled relation to part 27 of the connector, comprises an extension 38 formed integrally with leg 39 of the bifurcated shank. The lower end of this extension is provided with a laterally projecting lug 40 adapted to extend between the legs of the U-shaped body portion 34 of the contact block and to engage the underside of the transverse portion 35 thereof as indicated in Fig. 8. Thus, 40 when the nut has been turned off or removed from the bifurcated shank of clamp part 27, the nut and contact block will be supported on the lug 40 so that the parts of the connector will not become disassociated while the lineman is in 45 the act of attaching the conductors by means of this connector.

50 55 The connector as illustrated in Fig. 8, is in condition or prepared to receive the conductors of Figs. 1 and 2. When the connector has been placed over the conductor with the legs of the bifurcated shank straddling the same, the nut may be threaded on the shank after which the other conductor may be inserted between the legs, the conductors placed one on the other in centered relation as shown in Figs. 1 and 2; and the nut drawn up tightly to clamp them firmly and positively together.

60 65 In Figs. 10 to 13, inclusive, a connector 42 is shown embodying a still further modified form of the invention. This connector comprises clamp parts 43 and 44, and means 45 for holding these parts in assembled relation when prepared for attachment to or removal from conductors 2 and 3.

70 75 Clamp part 43 comprises a bifurcated internally threaded member 46 having wrench flats 47 and a conductor receiving recess or seat 48 at its upper end.

Clamp part 44 comprises a threaded member 49 adapted to be threaded into or out of clamp part 43 and a contact block 50 which is swivelly connected to the upper end thereof as at 51.

75 Contact block 50 may be made in the form of a disc from metal, such as copper, and provided

with curved openings 52 through which the legs of bifurcated member 46 may pass and permit movement of the block or disc as member 49 is threaded into or out of the bifurcated members. 5 Disc or block 50 may be provided with a recess or groove 53 which forms a seat for conductor 3.

Means 45, which is provided to maintain the clamp parts in assembled relation when member 49 is threaded out of member 46, may include an 10 upwardly curved lug 54 formed integrally with one of the legs of member 46 adapted to hook under one side of disc 50 when clamp part 44 is in the position indicated in broken lines in Fig. 11. Another lug 55, which is curved downwardly, may 15 be provided adjacent to lug 54, to prevent clamp part 44 from being pulled off lug 54. Since the clamp parts cannot be accidentally disassociated from each other, the linemen may work unhampered by the possibility of losing one or the other 20 of the clamp parts while engaged in the act of attaching the same to connectors.

The connector shown in Figs. 10 and 11 operates in substantially the same manner as the connectors previously described. For example, if part 25 49 and block 50 are in the broken line position indicated in Fig. 11, the bifurcated member 46 is slipped over conductor 3 and member 49 threaded into the same. Conductor 2 is then inserted and part 49 drawn up tightly by means of a wrench, 30 whereby the conductors are joined and clamped together firmly and positively as shown in Figs. 10 and 11.

While several connectors embodying different forms of the invention have been shown and described, it is to be understood that the invention is not limited to the specific details and arrangement of parts illustrated, and that various modifications and changes may be made without departing from either the spirit or the scope of the 40 invention. It is desired, therefore, that only such limitations shall be placed on the invention as are imposed thereon by the prior art and the appended claims.

What I claim as new and desire to secure by 45 Letters Patent is:

1. A solderless connector comprising an internally threaded bifurcated member adapted to receive conductors to be joined, a bolt adapted to be threaded into said member, a contact block 50 having a swivel connection with the end of the bolt adapted to move between the legs of the bifurcated member as the bolt is threaded into or out of the same, and means on the bifurcated member for holding the contact block, bolt and 55 bifurcated member in assembled relation when the bolt is disengaged from the internal threads of said bifurcated member.

2. A solderless connector comprising an internally threaded bifurcated member adapted to receive conductors to be joined, a bolt adapted to be threaded into said members, a contact block having a swivel connection with the end of the bolt adapted to move between the legs of the bifurcated member as the bolt is threaded into or out of the same, and a lug on said bifurcated member adapted to hold the bolt and contact block in assembled relation to the bifurcated member when said bolt is disengaged from the internal threads of said member.

70 3. In a device of the kind described, a keeper lug having a U-shaped portion formed by spaced legs connected at one end by a bight, the inner walls of the legs being segmentally screw-threaded to form a longitudinally extended screw-way, 75 the spacing of the legs providing a passage for

the reception of wires and the inner face of the bight providing a wire seat, the end of one of the legs being extended and turned perpendicularly to form a retaining lip, a press-block pierced by a central bearing socket, and slots 5 laterally spaced to register with and slidably engage the legs of the keeper lug, the press-block being thereby adapted for such slidable engagement and permanently though freely anchored to the extended leg of the lug through 10 said retaining lip, and a press-screw having its working end journaled through the bearing socket of the press-block and upset to rotatively anchor it to the block, the said screw engaging the screw-way of the keeper lug. 15

4. In a device of the kind described, a keeper lug comprising a U-shaped portion including spaced, parallel legs connected by a bight, the inner face of the latter forming a wire seat and the spacing of the legs forming a wire passage, 20 the inner faces of the legs being longitudinally and segmentally threaded to form a screw-way directed towards the wire seat of the bight, the end of one leg being extended and turned perpendicularly to form a retaining lip, a press-block pierced by slots 25 adapted to register with and slidably engage the legs of the keeper lug, that leg of the lug carrying the retaining lip being passed through one of the slots of the press-block and permanently and slidably anchored to the block through the said retaining lip, by which arrangement the said block may be moved away from the end of the other leg for the admission of wires to the wire seat, or may be closed upon that other leg and pressed 30 towards the wire seat, and a press screw adapted and arranged to engage the screw-way of the keeper lug when the press-block is closed on the shorter leg, the end of the press screw being rotatively anchored to the said press block. 40

5. In a device of the kind described, a U-shaped keeper lug comprising spaced legs and a connecting bight, the end of one of the legs being extended and turned out to form a retaining lip, the inner sides of the legs being concaved longitudinally and segmentally threaded to form a screw-way directed towards the bight, a press-block having a central bearing socket and laterally spaced marginal slots for slidably engaging the legs of the lug, the said retaining 50 lip and connected leg of the lug being thus passed through one of the slots of the press-block and permanently and freely anchored thereto whereby the opposite margin of the block may be swung up and the slot at that margin 55 may be passed over the opposite leg of the lug and the block slid bodily over the legs toward the said bight, and a press-screw fitted to the screw-way of the lug, the end of the screw being journaled through the said bearing socket of the press block and upset for rotatively anchoring the screw to the block. 60

6. In a device of the kind described, a keeper lug including a U-shaped portion of spaced and parallel legs connected by a bight, the inner walls of the legs being segmentally screw-threaded to form a screw-way, the end of one of the legs being extended and turned perpendicularly to provide a retaining lip, a slotted press-block 65 slidably mounted by its slots upon the legs and held in that relation by the retaining lip and a press-screw for the said screw-way for forcing the press-block towards the bight, the inner end of the screw being rotatively anchored to the press-block. 70

7. In a device of the kind described, a keeper lug including a U-shaped portion of spaced and parallel legs connected by a bight, the inner walls of the legs being segmentally screw-threaded to form a screw-way, the end of one leg being turned perpendicularly to form a retaining lip, the inner faces of the legs being tapped seg-

mentally to provide a screw-way towards the bight, a slotted press-block slidably mounted upon the legs and retained by the retaining lip, and a press-screw utilizing the screw-way for forcing the press-block towards the bight. 5
